VERTICAL PUSH-BUTTON ASHTRAY
Guido Reuge, Sainte-Croix, Switzerland, assignor to
Reuge S.A., Sainte-Croix, Canton of Vaud, Switzerland,
a Swiss corporation

Filed Apr. 18, 1962, Ser. No. 188,430
Claims priority, application Switzerland Apr. 21, 1961
2 Claims. (Cl. 84—95)

The subject of the present invention is a vertical push-button ashtray wherein a helicoidally-threaded pin is actuated by the push-button to rotate a disc-shaped lid, assembled on the end of said pin by a free wheel, inside a receptacle designed to receive the ashes, the whole set on a base containing a spring music-box.

This ashtray is characterized in that it comprises a vertical plunger coaxial to the push-button pin and having, at the end located in the base, means cooperating with a mechanism winding the spring of the music-box.

The attached drawing shows, by way of example, four embodiments of the ashtray forming the subject of the present invention.

FIGURE 1 is a partially-sectional side elevation of the first embodiment.

FIGURE 2 is an enlarged sectional view of a detail of FIG. 1.

FIGURE 3 is a view of the second embodiment similar to that of FIG. 1.

FIGURES 4 and 5 are views similar to that of FIG. 1, of the third and fourth embodiments.

FIGURE 6 is a partial sectional view of a detail of another embodiment.

The ashtray shown is of the type having a vertical push-button 1 with a helicoidally-threaded pin 2 controlled by the push-button to rotate a disc-shaped cover 3 assembled on the end of pin 2 by a freewheel mechanism in known manner as shown in detail in FIG. 2. Lid 3 covers a receptacle 4 designed to receive the ashes. A subjacent base 5 encloses a spring music-box generally, indicated at 6. A cylindrical casing encircles receptacle 4 and base 5.

A member fixed to the end of pin 2 of push-button 1 extends through disc 3 and is used to actuate a plunger 8 to wind up music-box 6 as will be described further on. This member fixed to pin 2 is made up of a tapped socket 9 screwed to the threaded end 10 of pin 2 and having a head 11 protruding below disc 3. This head socket is independent of disc 3 so that when the latter receives a rotation movement from pin 2 via the known freewheel mechanism, head 11 remains stationary with respect to disc 3 which turns. The freewheel mechanism comprises a cam 12 cooperating with balls 13 inside a casing 14 fixed to disc 3 so as to block the balls against the inside wall of the case when said cam 12 turns in the direction which rotates the disc and to free the balls when this cam no longer turns, the disc then being free.

The lower portion of plunger 8 is equipped with a rack 15 meshing with a gearwheel 16 of the spring-winding mechanism of music-box 6. This gearwheel 16 is clamped to the barrel axis of the spring in case 17. A barrier section 18 is also attached to the spring axis and serves to limit the rotation angle of wheel 16 by butting against a pin 19. This rotation angle corresponds to a piece of music, i.e. to one turn of the pin drum 6' of music-box 6.

A spring blade 20 is attached to the bottom of receptacle 4 and its bent free end leans against plunger 8 to cooperate with a slot 21.

The described embodiment works as follows:

By pushing down the push-button 1, the threaded pin 2 is rotated in known manner, which pin rotates by means of said freewheel mechanism the disc 3. During pushing, the plunger 8 is forced down by means of the head 11 of

2

socket 9, whereby substantially no friction occurs between head 11 and the end of plunger 8.

Rack 15 then rotates wheel 16 and simultaneously the barrier section 18 until an edge of this section butts against pin 19, as shown in FIG. 1. By releasing push-button 1, lid 3 is moved back to its closed position by a retracting spring (not shown) and plunger 8 rises again as the music plays, drawn by gearwheel 16.

While moving towards the bottom of plunger 8, slot 21 passes under the end of spring 20 at a given time which causes braking. The music-box spring is not yet completely wound up to play a tune and if push-button 1 is not pressed further down, plunger 8 could be kept in this position by spring 20. This arrangement permits the ashtray to be used without actuating the music-box each time.

In the embodiment shown in FIG. 3, head 11 acts on a plunger 8' whose end located in base 5 is linked to a lever winding the music-box spring by means of a link 23. By pressing push-button 1 of the ashtray, head 11 presses plunger 8' which, in going down, moves lever 22 from the straight-line position to the dotted-line position, winding up and thus releasing the music-box which plays until lever 22 has come back in its original position.

In the embodiment of FIG. 4, casing 7 has an aperture 23' through which appears a drum 24 rotatably mounted on a vertical axis and driven by means of gearing 25 from a gearwheel 26 clamped to shaft 27 of roller 6'. Drum 24 may be transparent and may be decorated with pictures, ornamental designs or commercial advertisements, a source of light, for example, being inside this drum. The other members are the same as those of the embodiment of FIG. 1.

In the embodiment of FIG. 5, base 5' is made up of a drum surrounding receptacle 4' of the ashtray. There are pictures, ornamental designs or commercial advertisements on the exterior surface of this drum 5' which is assembled in a casing 29 equipped with an aperture 30 allowing thus exterior surface to be seen. Casing 29 has legs 31 and holds receptacle 4' in its upper portion, as well as the pushbutton mechanism of the ashtray. Instead of being assembled in a casing, the receptacle could be supported by small pillars which would permit all of the drum to be seen. The receptacle could also be supported by a transparent cylinder.

The music-box is attached to receptacle 4', inside said drum 5' the bottom of which carries a pinion 32 engaged with a gear-train driven by gearwheel 33 fixed to the shaft of rollers 6'. When the music-box is in operation, it rotates drum 5' by means of the above-described gears.

In the modification shown in FIG. 6, the music-box is assembled at the bottom of base 5 with the axis of roller 6' vertical. In this case, rack 15 of plunger 8 meshes with a pinion 34 fastened directly to axis 35 of the barrel.

The motor spring could also be in 6' and the barrel would not be necessary.

Instead of actuating the plunger with the aid of a member fixed to the push-button pin, independent of the disc 3, such as head 11, the plunger could have at least one rotatable portion such as a ball against which the central portion of the rotatable disc would press, for example the hub of the disc or the top of case 14. The plunger could also be rotatably assembled, for example, on ball-bearings. This arrangement would have the same purpose as that described previously, i.e. to eliminate friction between the push-button and the device controlling the winding mechanism of the music-box.

What I claim is:

1. An ashtray comprising a vertical push-button, a helicoidally-threaded spindle actuated by said push-button, a disc-shaped lid mounted on said spindle through a freewheel mechanism, a receptacle for ashes wherein said

lid and said mechanism are positioned, a base upon which all of said elements are mounted, a spring-actuated music-box having a winding mechanism located in said base, and a vertical slideable plunger coaxial to said spindle, said plunger having an end extending into said base and cooperating with said winding mechanism, said spindle being provided with a threaded end, a socket on said threaded end extending through said lid, which socket has a head engaging and actuating said plunger without friction, said plunger being provided with a slot, a leaf-spring having a free end located in said slot to hold said plunger in a predetermined position whereby said music-box does not play. 10

2. An ashtray as set forth in claim 1, wherein said music box is arranged vertically in said base, parallel to 15 said plunger.
